DESIGN FOR AN ANNUNCIATOR CHIME

Carlton L. McMullen, West Hartford, Conn.

Application October 12, 1939, Serial No. 87,630

Term of patent 14 years

To all whom it may concern:

Carlton L. McMullen, a citizen of the Dominion of Canada, who has declared his intention of becoming a citizen of the United States, residing at West Hartford, in the county of Hartford and State of Connecticut, has invented a new, original, and ornamental Design for Annunciator Chimes, of which the following is a specification, reference being had to the accompanying drawing, forming a part thereof.

The figure is a perspective view of the an-

nunciator chime showing my new design.

The design comprises a central portion having similar upper and lower extensions of slightly reduced size but generally conforming to the outline of the central portion. The back face of the design is substantially flat.

I claim:

The ornamental design for an annunciator chime, as shown and described.

CARLTON L. McMULLEN.
